J. B. NORTON

RECORDING AND INDICATING DEVICE FOR FIRE EXTINGUISHERS

Filed Jan. 18, 1924

Fig. 2.

Fig. 4.

Irweitor:
Jerome B. Norton.

UNITED STATES PATENT OFFICE.

JEROME B. NORTON, OF ROSLINDALE, MASSACHUSETTS, ASSIGNOR TO BADGER FIRE EXTINGUISHER COMPANY, OF BOSTON, MASSACHUSETTS, A CORPORATION OF MASSACHUSETTS.

RECORDING AND INDICATING DEVICE FOR FIRE EXTINGUISHERS.

Application filed January 18, 1924. Serial No. 687,158.

To all whom it may concern:

Be it known that I, JEROME B. NORTON, a citizen of the United States, residing at Roslindale, in the county of Suffolk and State 5 of Massachusetts, have invented new and useful Improvements in Recording and Indicating Devices for Fire Extinguishers, of which the following is a specification.

This invention relates to a recording and 10 indicating device for portable, chemical fire extinguishers.

In operating certain types of portable, chemical fire extinguishers it is necessary to hold the extinguisher in a tipped or inverted 15 position in order that the chemicals and water which are normally held separated from each other within said extinguisher may be united to form the fire extinguishing fluid, and when the extinguisher has been so tipped and said chemicals and water united, 20 it is necessary to recharge the extinguisher with fresh chemicals and water in order that said extinguisher will function properly when again employed. It is furthermore 25 very important that this type of fire extinguisher shall be recharged periodically in order that the user may be assured that the extinguisher will function efficiently when employed in an emergency.

With these facts in mind, it will be evident 30 that it is important that a record shall be kept upon the extinguisher of the date when the latter is last recharged, and it is also desirable that a means shall also be provided for automatically indicating the fact 35 that the extinguisher has been tipped sufficiently to mix the water with the chemicals even though all of the contents may not have been used.

The object, therefore, of this invention is 40 to provide a device which may be clamped rigidly in position upon a portable chemical fire extinguisher, said device being provided with an indicator upon which is recorded the 45 date when the fire extinguisher is charged, said date being visible through an opening in the cover of the device, the indicator being mounted within the casing of the device in such a manner that when the fire extinguisher is tipped, as is necessary in operating 50 the same, said indicator will also tip a sufficient amount to move from view that portion of the surface thereof upon which the charging date is recorded, and at the

same time move into view a colored surface, 55 and said colored surface will continue to remain in view and thereby indicate that the extinguisher has been used, even after said extinguisher has been returned to its normal upright position and until it has been recharged, when the new date is placed upon the indicator and the latter is reset in its normal position by the person who recharges the extinguisher.

The invention consists in the combination and arrangement of parts as set forth in the following specification and particularly as pointed out in the claims.

Referring to the drawings:

Figure 1 represents a front elevation of the upper portion of a portable, chemical fire extinguisher of well known construction, a recording and indicating device embodying my invention being illustrated clamped thereto.

Fig. 2 is a central vertical section through the device as taken on the line 2—2 of Fig. 1.

Fig. 3 is a front elevation of the device with the cover thereof removed and with the indicator located in its normal position.

Fig. 4 is a front elevation with the cover removed, but illustrating the indicator in its tipped position.

Like numerals refer to like parts throughout the several views of the drawings.

In the drawings, 5 represents the upper portion of a portable, chemical fire extinguisher of well known construction, 6 represents a cover for said extinguisher and 7 represents a handle portion formed integral with said cover. The recording and indicating device of this invention embodies therein a casing 8 which is rigidly secured to the handle portion 7 of the fire extinguisher 5 through the medium of a suitable clamp 9, the latter embodying therein a portion 10 which is formed integral with the casing 8, and a cap 11, and the handle portion 7 is clamped securely between the portion 10 of the casing 8 and the cap 11 through the medium of suitable screws 12.

The casing 8 is provided with a suitable chamber 13 therein at the center of which is a boss 14 which is formed integral with the rear wall of the casing 8. A cover 15 is provided for the front of the casing 8, said cover being detachably secured to said casing by a suitable screw 16 which engages

the boss 14. The cover 15 is provided with a circular opening 17 therein and a plate 18 of suitable transparent material, as for example, glass or celluloid, is secured in any suitable manner between the cover 15 and the front edge of the casing 8, said transparent material extending across said opening 17.

The boss 14 within the chamber 13 is provided with a shouldered portion 19 formed thereon, and an indicator 20 is loosely mounted to rotate upon said shoulder. The indicator 20 embodies therein a front member 21 constructed of a suitable sheet material, preferably paper or cardboard which is stiffened and strengthened by a similarly shaped backing member 22, preferably constructed of sheet metal. The front surface of the indicator 20 is provided with a recording surface 23 preferably circular in form and approximately the size of the opening 17 in the cover 15, and said recording surface has the word "Charged" clearly printed thereon beneath which is a clear space upon which the date when the fire extinguisher is charged or recharged may be recorded as indicated. The remainder of the front surface of the indicator 20, or at least the portion 24 thereof, is colored, preferably red.

Rigidly fastened to the rear of the indicator 20 is a suitable weight 25 which normally acts to hold said indicator in the position illustrated in Figs. 1 and 3, and also to rock said indicator into the position illustrated in Fig. 4 when the fire extinguisher 5 is tipped to approximately an inverted position. A spring 26 is mounted in the chamber 13 of the casing 8, being positioned therein upon a post 27, preferably formed integral with the rear wall of said casing, and one end of said spring is bent at 28 and yieldingly engages the periphery of the indicator 20. A pin 31 holds the indicator 20 in its normal position as illustrated in Figs. 1 and 3. The other end portion 29 of the spring 26 bears against the inner wall of the casing 8 as illustrated in Fig. 3. The indicator 20 has a notch 30 located at a suitable position in the periphery thereof and when the fire extinguisher 5 is inverted in operating the same, said indicator will rock upon the shoulder 19 of the boss 14 until an edge portion thereof engages a stop pin 32 whereupon the portion 28 of the spring 26 will spring into said notch 30, and said indicator will thereafter be held locked securely in its tipped position, at which time the colored surface 24 of said indicator will be visible through the opening 17 in the cover 15, and said colored surface will continue to be visible through said opening even after the extinguisher 5 has been returned to its normal upright position. The colored surface thus

displayed will be a signal that the fire extinguisher has been tipped and that it should be recharged before being again operated, and when said extinguisher is recharged, the date is recorded upon the recording surface 23 of the indicator 20 and the latter is again returned to its normal position as illustrated in Figs. 1 and 2, in which position the recharging date will be visible through the opening 17.

It will be seen that a fire extinguisher equipped with the device of this invention will always have the charging date clearly visible thereon and if time elapses and the fire extinguisher has not been used, it can easily be determined when said extinguisher should be again recharged. On the other hand, if the fire extinguisher is used, and has been tipped a sufficient amount to mix the chemicals and water, that this fact will be indicated by the display of the colored surface of the indicator through the opening 17 and the display of said colored surface will be a reminder to the proper persons that the fire extinguisher should be immediately recharged.

I claim:

1. A recording and indicating device of the character described comprising, in combination, a casing and a gravity actuated indicator pivotally mounted in said casing and adapted to rock therein when said casing is tipped beyond a predetermined angle.

2. In combination, a fire extinguisher and an indicating device mounted upon said fire extinguisher and embodying therein a casing and an indicator rotatably mounted in said casing and adapted to automatically display a visible signal when said fire extinguisher is tipped beyond a predetermined angle.

3. A recording and indicating device of the character described comprising, in combination, a casing, a gravity actuated indicator mounted in said casing and adapted to rock therein when said casing is tipped and means to lock said indicator in a tipped position to prevent a return movement thereof when said casing is returned to its normal position.

4. A recording and indicating device of the character described comprising, in combination, a casing, an indicator mounted in said casing, means fast to said indicator adapted to rock the latter when said casing is tipped and means to lock said indicator in a tipped position to prevent a return movement thereof when said casing is returned to its normal position.

5. A recording and indicating device of the character described comprising, in combination, a casing, an indicator mounted in said casing, a weight fast to said indicator and positioned to rotate the latter when said casing is tipped and means to lock said indi-

cator in a tipped position to prevent a return movement thereof when said casing is returned to its normal position.

6. A recording and indicating device of the character described comprising, in combination, a casing, an indicator mounted in said casing, a weight fast to said indicator and positioned to rotate the latter when said casing is tipped, means to loosely hold said indicator in its normal position and means to automatically lock said indicator in a tipped position to prevent a return movement thereof when said casing is returned to its normal position.

15 7. A recording and indicating device of the character described comprising, in combination, a casing, an indicator mounted in said casing, a weight fast to said indicator and positioned to rotate the latter when said casing is tipped and a spring yieldingly engaging said indicator and co-operating therewith to automatically lock the same in a tipped position to prevent a return movement thereof when said casing is returned to its normal position.

20 8. A recording and indicating device of the character described comprising, in combination, a casing, an indicator mounted in said casing and provided with a notch in the periphery thereof, a weight fast to said indicator and positioned to rotate the latter when said casing is tipped and a spring yieldingly engaging the periphery of said indicator and interlocking with said notch when said indicator is located in a tipped position thereby preventing a return movement of said indicator to its normal position when said casing is returned to its normal position.

25 9. A recording and indicating device of the character described comprising, in combination, a casing provided with an opening therein, a gravity actuated indicator mounted in said casing and provided with a recording surface thereon normally visible through said opening, said indicator being adapted to rock within said casing when the latter is tipped to move the recording surface thereof out of view through said opening and means to automatically lock said indicator in a tipped position to prevent a return movement thereof when said casing is returned to its normal position.

30 10. A recording and indicating device of the character described comprising, in combination, a casing provided with an opening therein, a gravity actuated indicator mounted in said casing and provided with a recording surface thereon normally visible

through said opening, said indicator also being provided with an indicating surface thereon and being adapted to rock within said casing when the latter is tipped to move the recording surface thereof out of view through said opening and to move said indicating surface into view through said opening and means to automatically lock said indicator in a tipped position with said indicating surface in view through said opening.

35 11. A recording and indicating device of the character described comprising, in combination, a casing provided with an opening therein, a gravity actuated indicator mounted in said casing and provided with a recording surface thereon normally visible through said opening, said indicator also being provided with an indicating surface thereon and being adapted to rock within said casing when the latter is tipped to move the recording surface thereof out of view through said opening and to move said indicating surface into view through said opening and a spring yieldingly engaging said indicator and co-operating therewith to automatically lock the same in a tipped position to prevent a return movement thereof when said casing is returned to its normal position.

40 12. A recording and indicating device for a fire extinguisher comprising, in combination, a casing provided with an opening therein, means to clamp said casing to a fire extinguisher, a gravity actuated indicator mounted in said casing and provided with a recording surface thereon normally visible through said opening, said indicator also being provided with a colored surface thereon and being adapted to rock within said casing when said fire extinguisher is tipped to move the recording surface of said indicator out of view through said opening and to move said colored surface into view through said opening, a spring yieldingly engaging the periphery of said indicator and interlocking therewith when the latter is located in a tipped position thereby preventing a return movement of said indicator to its normal position when said fire extinguisher is returned to its normal position.

45 In testimony whereof I have hereunto set my hand in presence of two subscribing witnesses.

JEROME B. NORTON.
